DISCHARGE DEVICE AND ELECTRODE

Daniel S. Gustin, Bloomfield, N. J., assignor to Westinghouse Electric & Manufacturing Company, East Pittsburgh, Pa., a corporation of Pennsylvania

Application September 2, 1937, Serial No. 162,087

3 Claims. (Cl. 176—126)

This invention relates to discharge devices, and more particularly, to electrodes therefor which will not disintegrate under the extreme conditions to which they may be subjected in service.

The principal object of my invention, generally considered, is the provision of an improved form of electrode for discharge devices, which has a relatively large surface area, which retains the electron emission material, and which occupies a relatively small space.

Another object of my invention is the provision of an electrode for discharge devices formed of fine tungsten wire braided into a sleeve or ribbon, thereby making the surface area large while maintaining the volume small, so as to facilitate heating to the proper emission temperature, and at the same time providing the desired area for the emission.

A further object of my invention is the formation of a discharge device having electrodes, each consisting of braided tungsten wire formed into a sleeve or hollow cylinder, open or closed at both ends, and impregnated with or containing a quantity of electron emission material, each cylinder being supported from a lead wire and disposed with its axis transverse to that of the envelope.

Other objects and advantages of the invention relating to the particular arrangement and construction of the various parts will become apparent as the description proceeds.

Referring to the drawing illustrating my invention:

Fig. 1 is a longitudinal sectional view of one end portion of a discharge device having electrodes embodying my invention, one electrode being shown in side elevation with parts broken away.

Fig. 2 is a longitudinal sectional view of the same end portion of the device shown in Fig. 1, said view, however, being taken at right angles to that of Fig. 1 and showing the electrode in end elevation.

Fig. 3 is a greatly enlarged elevational view of a portion of the sleeve or ribbon, formed by braiding fine wire of tungsten or other suitable metal, which serves for the construction of the electrode embodying my invention.

Fig. 4 is an edge view of the portion of the sleeve or ribbon shown in Fig. 3.

Fig. 5 is a view corresponding to Fig. 1, but showing a modified form of electrode and lead wire removed from the enclosing envelope.

Fig. 6 is a view similar to Fig. 5, but showing still another form of my electrode.

Referring to the drawing in detail, and first considering the embodiment of my invention illustrated in Figs. 1 to 4 inclusive, there is shown one end portion of a discharge device or tube 10 comprising a glass or vitreous envelope 11 into each end of which extends a leading-in conductor 12 carrying an electrode 13, only one of which is illustrated, as by means of a U-shaped piece of wire 14, the central portion of the wire 14 being welded or otherwise secured to the inner end of the leading-in conductor 12, as indicated at 15 and the arms welded or otherwise secured to the electrode 13 adjacent its ends, as indicated at 16 and 17.

In the present embodiment, the electrode 13 is constructed from a ribbon 18 formed by braiding fine wires 19, desirably made of tungsten, but which may, if desired, be made, for use under certain circumstances, of other suitable metals such as platinum, molybdenum, or nickel, as indicated in Figs. 3 and 4. In other words, a series of fine wires 19 may be woven or braided together, diagonally or otherwise, to form a sort of metallic cloth or ribbon 18, which is then bent to hollow cylindrical form, as indicated in Figs. 1 and 2, the meeting edges of the ribbon being secured together by welding or in any other desired manner, as indicated at 20, and the end portions of said joined edges being united to the leading-in conductor 12 in any convenient or desired manner, as indicated by the intermediate conductor 14. If desired, a seamless sleeve may be woven from the wires 19 and directly united to the conductor 12 or intermediate wire 14.

The electrode 13, on account of its manner of formation, provides a relatively large effective area to which may adhere electron emission material, such as a mixture of the alkaline earths, say, barium oxide and strontium oxide. These oxides may be applied to the braided electrode 13, by dipping the same in, or spraying with, a solution of compounds of alkaline earth metals and igniting to leave the oxides thereon.

For example, a solution of the nitrates of barium and strontium may be applied to the braided electrode 13, after which the same is ignited to leave the oxides thereon. Or a suspension of the carbonates or other compounds of said alkaline earth metals may be applied to the electrode and subsequently decomposed either by direct ignition, or by forming a discharge between the electrodes 13 in the envelope 11.

A further way of applying the electron-emis-

sion material to the hollow cylindrical electrodes 13, is by filling said hollow electrodes with the material and closing the ends to prevent loss. On account of the weaving of the wires 19 to form the electrodes 13, there is plenty of space therebetween for allowing any electron-emission material enclosed in the hollow cylinder 13 to operate for the generation and release of electrons.

10 Turning now to Fig. 5, we find an electrode 13^a supported from a leading-in conductor 12^a by means of a U-shaped wire 14^a. The electrode 13^a is constructed exactly like the electrode 13 of the previous embodiment, except that flange 15 20^a, formed by the union of the edge portions of the ribbon or metallic cloth 18, is slightly cut away at the ends, and caps 21 and 22 are applied over the hollow cylindrical cathode 13^a to prevent loss of electron emission material 23 housed 20 therein. Although caps have been shown, it will be understood that plugs may be employed instead for closing the ends of the cylindrical electrode.

25 Referring now to the embodiment of my invention illustrated in Fig. 6, there is shown an electrode 13^b supported from the leading-in conductor 12^b by means of a U-shaped wire 14^b. The electrode 13^b of the present embodiment is identical with the electrode 13 of the first embodiment except that the flange portion 20^b, formed at the joint between the meeting edges of the wire ribbon or cloth 18 forming the hollow cylindrical electrode, is cut away and the end portions of said electrode closed about electron 30 emission material 23^b contained therein by pinching or crimping the ends of said cylindrical portion as indicated at 21^b and 22^b.

35 Instead or in addition to having the hollow cylindrical electrodes 13, 13^a, and 13^b filled with electron emission material, it will be understood that such material may be applied to the outer surface or the mesh of the electrodes impregnated with said material, as described in connection with the embodiment of Figs. 1 to 4 inclusive.

40 From the foregoing disclosure, it will be seen that I have devised an improved form of discharge device having electrodes adapted to function as electron emitting devices. These elec-

5 trodes have large surface areas for retaining the emission material and occupy relatively small spaces, being desirably woven from the fine tungsten wire into a foraminous sleeve, or into a ribbon and subsequently formed into such a sleeve or hollow cylinder. On account of the construction, heating is facilitated, thereby making it possible to secure proper emission temperatures in short periods of time. The hollow cylinders produced are not only ideal holders for the emission material, but such material may be impregnated in the interstices of the weave or held on the exterior surface without danger of loss.

10 15 Although preferred embodiments of my invention have been disclosed, it will be understood that modifications may be made within the spirit and scope of the appended claims.

I claim:

1. An electric discharge device comprising a sealed envelope, a leading-in conductor extending into each end of said envelope, an electrode secured to the inner end of each conductor, each electrode being formed of braided wire bent to cylindrical form with free edge portions overlapped and connected to form an outstanding flange portion and carrying electron-emission material, and connecting means between each electrode and its conductor comprising a U-shaped wire the arms of which are secured to the electrode flange and the intermediate portion of which is attached to the conductor.

2. An electric discharge device comprising a sealed envelope, a leading-in conductor extending into each end of said envelope, and an electrode secured to the inner end of each conductor by means of a U-shaped wire, the ends of which are secured to the said electrode and an intermediate portion of which is secured to said conductor, each electrode comprising a hollow metal cylinder with its axis, extending transverse to that of said envelope and provided with a radial flange to which the U-shaped wire is united.

3. An electrode comprising a hollow cylinder of braided tungsten wire with abutting flanges extending therefrom, and a U-shaped holding element secured to said flanges.

DANIEL S. GUSTIN.
